(No Model.)

M. RICHTER.

ADJUSTABLE BOLSTER HEAD FOR BEDSTEADS.

No. 262,121.

Patented Aug. 1, 1882

Fig. 1.

Fig. 2.

UNITED STATES PATENT OFFICE.

MORITZ RICHTER, OF NORWICH, CONNECTICUT.

ADJUSTABLE BOLSTER-HEAD FOR BEDSTEADS.

SPECIFICATION forming part of Letters Patent No. 262,121, dated August 1, 1882.

Application filed June 22, 1882. (No model.)

To all whom it may concern:

Be it known that I, MORITZ RICHTER, of 5
Norwich, in the county of New London and
State of Connecticut, have invented certain
new and useful Improvements in Adjustable
Bolster-Heads for Bedsteads, of which the fol-
lowing is a specification.

This invention has reference to an improved
head-bolster for bedsteads, that can be ar-
10 ranged higher or lower, so as to form not only
a support for the head, but also for the back,
when it is desired to sit up in bed. The head-
bolster is furthermore adapted to be swung up
against the head-board of the bedstead, so as
15 to expose a pillow-sham that is applied to the
under side of the bolster.

The invention consists of a spring-cush-
ioned head-bolster that is connected by piv-
oted links to the head-posts of the bedstead,
20 the upper half of the head-bolster being hinged
to the lower half, and provided with means
whereby the upper part may be set higher or
lower on the lower part. After use the entire
head-bolster is thrown upon the links and sup-
25 ported in upright position on the head-board
of the bedstead.

In the accompanying drawings, Figure 1
represents a perspective view of a bedstead
30 with my improved head-bolster shown as
thrown up against the head-board to expose
the pillow-sham. Fig. 2 is a vertical trans-
verse section of the head-bolster on a larger
scale; and Fig. 3 is a top view of the same
35 on a still larger scale, shown entirely opened.
Similar letters of reference indicate the cor-
responding parts.

A in the drawings represents a head-bolster
which is made of two sections, the upper sec-
40 tion, *a*, being hinged to the front end of the
lower section, *a'*, and properly spring-cush-
ioned and upholstered. The lower section, *a'*,
is permanently connected at the rear end to
the head-posts of the bedstead by means of
pivot-links *b b*.

45 The upper section, *a*, of the head-bolster A
is capable of being adjusted higher or lower,
or into nearly upright position on the lower
part, by means of side racks, *d d*, which are
pivoted to the frame of the upper section, *a*,
50 of the bolster, and drawn by spiral springs *d'*
against fixed studs *d²* of the lower section, *a'*,
of the bolster, as shown clearly in Fig. 2.

The pivoted rack-bars *d d* are connected at

their outer ends by a transverse rod, *e*, to
which is applied an operating-cord, *e'*, that 55
passes through openings of the frame of the
upper section of the bolster, so that the racks,
by taking hold of the cord *e'*, may be released
from the lugs *d²*, and then the upper section
of the bolster adjusted into higher or lower 60
position, as shown in dotted lines in Fig. 2.

For closing the sections of the head-bolster
entirely, the rack-bars are lifted by the cord *e'*
so as to clear the lugs *d²*, after which the up-
per section may be lowered down on the lower 65
section.

By a simple manipulation the bolster may
be set higher or lower, also into nearly verti-
cal position, in case the occupant desires to
sit up in the bed. After use, when the bed is 70
made up, the head-bolster is thrown on the
pivot-links into vertical position against the
head-board, in which case the bottom part of
the head-bolster A is exposed, to which the
75 pillow-sham is attached by safety-pins or other-
wise, so that a very neat appearance is im-
parted to the head-bolster.

Having thus described my invention, I claim
as new and desire to secure by Letters Patent—

1. The combination, with the head-posts of 80
a bedstead, of a head-bolster connected thereto
by pivot-links, so as to be capable of use as a
bolster or be adapted to be thrown up against
the head-board of the bedstead, substantially
as and for the purpose set forth. 85

2. The combination, with the head-posts of
a bedstead, of a head-bolster connected thereto
by pivot-links, and composed of an upper sec-
tion, a lower section hinged thereto, and means
whereby the upper section may be set higher 90
or lower on the lower section, substantially as
and for the purpose set forth.

3. The combination of a head-bolster, A,
composed of an upper hinged section, *a*, hav-
ing pivoted and spring-acted rack-bars *d d* and 95
an operating-cord, *e'*, and of a lower section,
a', having fixed interior lugs, *d²*, with exterior
pivot-links, *b b*, applied to the head-posts of
the bedstead, substantially as set forth.

In testimony that I claim the foregoing as 100
my invention I have signed my name in pres-
ence of two subscribing witnesses.

MORITZ RICHTER.

Witnesses:

PAUL GOEPEL,
SIDNEY MANN.
